DESIGN FOR A CONVERTIBLE GILET DRESS

Oscar Zaretzky, New York, N. Y.

Application September 1, 1939, Serial No. 86,992

Term of patent 3½ years

To all whom it may concern:

Be it known that I, Oscar Zaretzky, a citizen of the United States and a resident of the city of New York, in the county of Bronx and State of New York, have invented a new, original, and ornamental Design for a Convertible Gilet Dress, of which the following is a specification, reference being had to the accompanying drawing forming a part thereof:

Fig. 1 is a front view of a dress showing my new design with the gilet attached in position.

Fig. 2 is a rear view of the dress shown in Fig. 1.

Fig. 3 is a plan view of the gilet portion of the dress shown in Fig. 1.

I claim:

The ornamental design for a convertible gilet dress, substantially as shown.

OSCAR ZARETZKY.
